INVENTOR.

William R. Woodward,
By his attorney,

J.H. McCrady.

UNITED STATES PATENT OFFICE.

WILLIAM RUSSELL WOODWARD, OF BROCKTON, MASSACHUSETTS, ASSIGNOR TO
LEATHER STEEL PRODUCTS CO., OF BOSTON, MASSACHUSETTS, A CORPORATION
OF NEW YORK.

MAT.

1,414,243.

Specification of Letters Patent. Patented Apr. 25, 1922.

Application filed May 20, 1921. Serial No. 471,267.

To all whom it may concern:

Be it known that I, WILLIAM R. WOODWARD, a citizen of the United States, residing at Brockton, in the county of Plymouth and 5 State of Massachusetts, have invented certain new and useful Improvements in Mats, of which the following is a specification.

This invention relates to mats of the link type; that is, mats which consist of links of 10 such materials as leather, fibre, felt, metal and the like, these links being connected together to form a mat of the required shape and dimensions. The invention is especially concerned with the edge construction of such 15 mats where it is necessary to make bias cuts, curves, cutouts, and the like, as for instance, where the mat is to fit around a post or against an angular wall. It has been customary heretofore in making mats of this 20 character to make a bias cut, curve, cut-out, or the like by stepping the sections along the edge where this special construction is required. It is obvious that the pintle wires in these stepped sections cannot be manipulated 25 in the same way that they are in the regular or straight sided sections of the mat and it has been the practice therefore to put a burr or washer at the end of the pintle wire of each stepped section and head this 30 wire over. This construction is objectionable in that it detracts from the workman-like appearance of the mat, and more particularly because the burr or washer is liable to be knocked off or worn off and thus release 35 the segments in the section held by this particular wire. It is, therefore, the chief object of this invention to devise a construction that will overcome these difficulties.

40 The nature of the invention will be readily understood from the following description when read in connection with the accompanying drawings, and the novel features will be particularly pointed out in the appended claims.

45 Referring now to the drawings,

Figure 1 is a perspective view of a small part of the leather mat showing the construction embodying the present invention;

50 and

Fig. 2 is a plan view of the construction shown in Fig. 1.

The body portion of the mat shown is built in the usual manner and consists of sections

each consisting of a series of links made of 55 segments 2. The segments may be made of leather, fibre or any suitable material. The drawing shows only three sections designated respectively at 3, 4 and 5, it being understood, however, that as many sections 60 as desired may be used and that these sections may be made of any desired length. The adjacent sections are secured together by pintle wires or rods and these wires not only perform the function of securing the 65 links of one section to those of the next adjacent section, but also that of binding the segments of each section together. In the construction shown the sections 3 and 4 are secured together by the pintle wire 6. The 70 sections 4 and 5 are similarly connected by one leg 7 of another wire, and the section 5 is connected to its next adjacent section by the other leg 8 of this wire. At the time the 75 segments of the sections 4 and 5 are assembled the pintle wire 7-8 is bent into a U-form, the bridge portion 9 of this wire holding one end of the section, and after the assembling operation has been completed 80 the ends of the legs 7 and 8 are bent toward each other, as clearly shown in Fig. 2, and are connected by a sleeve or clip 10.

It will be observed that the small section of the mat shown has a straight left-hand edge and a stepped or bias cut right-hand edge. That is, the right-hand edge of the 85 section 4 is stepped toward the left with regard to the section 5, and the section 3 is similarly stepped with reference to the section 4.

90 As above stated, it has been usual heretofore to use washers or burrs at the ends of the pintle wires 6 and 12, respectively, of these stepped sections 4 and 3. According to the present invention, however, each of these wires is bent at right angles across the end of the stepped section and is hooked about the next adjacent wire. That is, the pintle wire 6 is bent so that a part 13 there-of lies across the face of the endmost segment 100 2 in the section 4, and the end portion of the part 13 has a hook or loop 14 formed therein which receives the pintle wire 7.

The pintle wire 12 of the section 3 has a bent portion 15 and a hook 16 curved about 105 the pintle wire 6, these parts corresponding to the parts 13 and 14 of the pintle wire 6. At the opposite edge of the mat the ends of

the pintle wires 6 and 12 are bent toward each other and the bent ends are connected by a clip 17 in exactly the same way that the wires 7 and 8 are secured together at this 5 edge of the mat.

In assembling the stepped sections the pintle wires of these sections preferably are bent, as indicated at 13 and 15, and these parts are slipped on to the pintle wires to 10 which they are to be connected at the proper point in the assembling of the segments 2. The operations at the opposite edge of the mat in this construction, therefore, are exactly like 15 those of the straight edged or standard mats.

It will now be appreciated by those skilled in this art that this invention provides a stepped edge construction for mats of this character which not only is much more substantial than those heretofore used, but that 20 it also presents a neater appearance and can be made more economically.

Having thus described my invention, what I desire to claim as new is:

25 1. A mat of the character described, comprising a series of link sections, pintle wires holding said sections together, said mat including a section stepped with reference to an adjacent section, and a connection at the 30 end of the stepped section securing the pintle

wire of the stepped section to the pintle wire of the next adjacent section.

2. A mat of the character described, comprising a series of link sections, pintle wires holding said sections together, said mat including one or more sections stepped with reference to an adjacent section, the pintle wire at the end of the stepped section or sections being united to the wire of the next 35 adjacent section. 40

3. A mat of the character described, comprising a series of link sections, pintle wires holding said sections together, said mat including one or more sections stepped with reference to an adjacent section, and a connection at the end of each stepped section additional to the links of said section securing the pintle wire of the latter section to the 45 pintle wire of the next adjacent section.

4. A mat of the character described, comprising a series of link sections, pintle wires holding said sections together, said mat including a section stepped with reference to an adjacent section, the pintle wire of the stepped section being bent at substantially 50 right angles across the end of said stepped section and hooked about the wire of the next adjacent section. 55

WILLIAM RUSSELL WOODWARD.
